UNITED STATES PATENT OFFICE

ELMER L. SMITH, OF LONGMEADOW, MASSACHUSETTS, ASSIGNOR TO PACKAGE MANUFACTURING COMPANY, OF SPRINGFIELD, MASSACHUSETTS, A CORPORATION OF MASSACHUSETTS

PAPER REGISTERING DEVICE

Application filed August 20, 1930. Serial No. 476,577.

This invention relates to registering devices for webs of such material as printed paper or cellophane and is of the type causing the web to be arrested in its travel at each cycle with the printed portion of the web in predetermined registration with those elements of the machine, such as cutting or printing devices, which are to operate on the web. In the preferred form, this control is attained by a photo-electric cell, the operation of which is controlled by the passage of some indicia on the web such as a portion of the printed matter.

One object of the invention is to provide a device of this character in which the stoppage of the paper is brought about by the deactivation of an electromagnet. It has been found that the deenergizing of a magnet is much more positive in action than its activation, particularly as in the latter case it is necessary to cause the armature of the magnet to move through an air gap by the force of a magnet. A further object is to provide a device of this character capable of operating upon web material without the necessity of providing perforations therein to control the electric circuit. A further object is to provide a device of this character which will be particularly adapted to the accurate registration for cutting of a web of cellophane having spaced printed areas simulating cigar bands.

The preferred form of the invention will now be described with reference to the accompanying drawings, in which:

Fig. 1 is a side elevation of a web registering device constructed in accordance with my invention;

Fig. 2 is a wiring diagram;

Fig. 3 is a top plan view corresponding to Fig. 1;

Fig. 4 is a detail section on line 4—4 of Fig. 1;

Fig. 5 is a detail of one form of web; and

Fig. 6 is a diagrammatic view illustrating one manner of producing intermittent motion of the web feed rolls.

Before describing the different parts of the mechanism in detail, its general operation will be considered. In the preferred form,

the web is fed by a pair of intermittently acting feed rolls driven so as to tend to deliver a length of web at each machine cycle slightly greater than that which is required. The feed rolls are of a nature permitting slippage when the web is restrained by a brake. This brake, according to my invention, is constantly urged into action by a spring, the tendency of which is normally counteracted by the attraction of an electromagnet for its armature. At each cycle of the machine, the passage past a photoelectric cell of an indicium such as a portion of a printed label on the web causes the electromagnet to be deenergized and permits the brake to be applied by the spring. The setting of the photo-electric cell is such that the deenergizing of the magnet occurs just prior to the normal stoppage of the web at each cycle, varying in amount depending upon the distance between the indicia on the web. The distance between indicia varies due to shrinkage or stretching of the web, and the function of the registering device is to cut varying lengths of web so that the line of cut is always spaced in a predetermined relationship to the printed portion of the label. The detailed mechanism by which this is accomplished will now be described.

The device is mounted upon a frame 10 which may be of any desired form. Journalled upon this frame are feed rolls 11 and 12 between which the web *w* is led. The web passes also over guide rolls 13 and 14 so as to be directed in proper relationship with the photo-electric cell and the brake to be described below. The feed rolls may be driven continuously but it is preferred to move them intermittently, the mechanism operating them being designed so that at each machine cycle they tend to feed a length of web slightly in excess of what is required. Before reaching the feed rolls the web passes over a plate 15 adjacent to which is a movable brake shoe 16. This brake shoe is shown as being mounted upon a lever 17 pivoted at 18 to the frame and urged in a direction to force the shoe toward the plate by a spring 19 strained between pin 20 on the lever and pin 21 on the frame. A link 22 is connected by pins 23 and 24 respectively to the lever 17 and to one arm 100

of a bell crank 25 pivoted to the frame at 26. The other arm of the bell crank bears a pin 27 running in a short slot 28 formed in a link 29 which is urged in a direction to keep one end 5 of the slot against the pin by a spring 30 fastened at one end to the pin 27 and at the other to a pin 31 on the link 29. This link is connected at 32 to the pivoted armature 33 of an electromagnet 34. During the normal 10 running of the machine, the magnet 34 is energized and the armature 33 is kept in the position shown in Fig. 1. In this position the pin and slot connection 27, 28 keeps the brake 16 out of contact with the web by 15 means of the linkage described. Once in every cycle of the machine's operation the magnet is deenergized, as will be described later, thus releasing the linkage and permitting the spring 19 to force the brake 16 toward the plate 15. After this has occurred 20 the armature is spaced from the magnet, and re-activation of the magnet is in general insufficient of itself to cause the armature to move through the air gap against the resistance of the spring 19. It is well known that 25 the attractive power of a magnet is very much greater when its armature is in contact with the magnet core than when there is an intervening air gap.

30 To replace the armature positively against the magnet, the following mechanism is provided. The end of the second arm of the bell crank 25 carries a pin 35 running in a slot 36 formed in a plate 37. This plate is attached to a link 38 which is pivoted at 39 to one arm of a bell crank lever 40 swinging on the frame at 41. The other arm of this bell crank carries a cam roll 42 running on a cam 43 fixed to the constantly rotating cam shaft 44. A spring 45 is strained between the second arm of the bell crank and a pin 46 on the frame and serves to keep the roll 42 constantly against its cam. The cam 43 has its surface formed so that once in each cycle of 40 operation the bell crank 40 will be rocked and the armature 33 replaced against the core of the magnet 34. The pin and slot connections 35, 36 and 27, 28 form lost motion connections between this cam and the magnet. The first 45 of these connections permits release of the armature upon de-activation of the magnet when the plate 37 has been moved to the left-hand end of its travel. Fig. 1 shows the plate at substantially the right hand end of its travel. The second lost motion connection 50 serves merely to prevent undue strain upon the armature when it is moved against the core, it being necessary merely to bring the armature into contact with the core without 55 more pressure than is afforded by the light spring 30.

55 Mounted adjacent to the path of travel of the web *w* at a point prior to the engagement of the web by the feed rolls is a photoelectric cell 50 mounted within a shield 51

having a hole 52 upon the side adjacent the web. A constant light source 53, which may be an incandescent lamp, is placed directly opposite this hole so that the cell will be illuminated at all times except when the light 70 is eclipsed by the passage of a printed portion of the wrapper over the hole. This printed portion of the web may be part of the regular design printed thereon or may 75 be an area darkened particularly for this purpose. It will be understood that instead of operating a photo-electric cell in this fashion it could be caused to operate by the passage of a transparent area in a normally opaque web or could be actuated by 80 reflected light instead of by transmitted light.

85 While the particular electrical connections of the photo-electric cell do not form a part of my invention but are of standard commercial nature, I have indicated diagrammatically in Fig. 2 one form of connection suitable for this purpose. The photo-electric cell 50 is connected through a grid glow tube 54 which serves as an amplifier to the coil of 90 a relay magnet 55, a transformer 56 furnishing the necessary electrical current. The connections shown are of such a nature that upon eclipse of the photo-electric cell the relay magnet is operated, attracting its armature 57 and releasing its contact arm 58 95 from the stationary contact arm 59. This opens the magnet circuit 60 and causes the armature 33 to be released.

100 The particular operation which is to be performed on the web may vary and the mechanism operating upon the web does not form a part of my invention. In Fig. 1 I have indicated at 61 a line of cut where the temporarily arrested web may be severed by any suitable device. If such a cutting 105 device is used, the registering device will cause the web to be severed at a predetermined point intermediate the printed areas *a* of the web *w*, as shown in Fig. 5. By shifting the photoelectric cell on the frame along the path of the web, the relation of the line of cut to the printed areas may be adjusted.

110 As stated above, it is preferable to operate the feed rolls intermittently as this causes the minimum slippage of the paper and introduces the least cause for error. Furthermore by using intermittently operated rolls the operation of the photoelectric cell may be caused to occur just prior to the stoppage of the rolls and therefore at a time when they are moving with a relatively slow 115 surface speed. This also assists in increasing the accuracy of the device. The particular form of mechanism for rotating the rolls may be varied as desired and I have indicated in Fig. 6 one method of operation merely in the interest of completeness of disclosure. In this diagram the roll 11 is shown as provided with a gear 62 meshing with a gear 63 which carries a ratchet 64. Rotat-

ing about the axis of this ratchet is pawl 65 mounted upon a pawl carrier 66. Pawl carrier 66 is oscillated once during each cycle of the machine and for this purpose is shown 5 as connected by a link 67 connected to a crank 68 which is mounted upon a continuously rotating shaft 69.

I claim:

1. A web registering device comprising a 10 pair of web feed rolls, mechanism for rotating the rolls during each cycle of the machine's operation an amount slightly in excess of that required for feeding one unit of web under normal conditions, a brake adapted to stop the feeding movement of the web, a spring tending to set the brake, a magnet normally holding the brake against the action of the spring, and means responsive to the passage of web-carried indicia for releasing the magnet and thus permitting the spring to set the brake and interrupt the travel of the web.
2. A web registering device as claimed in claim 1 having mechanism periodically acting 25 to reset the magnet after its release.
3. A web registering device as claimed in claim 1 in which the indicia-responsive means comprises a photo-electric cell controlled by variations in light transmitted 30 through the web.
4. A web registering device comprising a pair of intermittently actuated web feed rolls, a brake adapted to stop the feeding motion of the web so that the feed rolls 35 will slip upon it, a spring tending to set the brake, a magnet normally holding the brake against the action of the spring, and means responsive to the passage of web-carried indicia for releasing the magnet during 40 the time just prior to the stoppage of the feed rolls and thus permitting the spring to set the brake and interrupt the travel of the web.
5. A web registering device as claimed in claim 4 having mechanism periodically acting 45 in timed relation to the feed rolls to reset the magnet after its release.
6. A web registering device as claimed in claim 4 in which the indicia-responsive means comprises a photo-electric cell controlled by variations in light transmitted through the web.
7. A web registering device comprising web feeding means, a photo-electric cell controlled by variations in light caused by the passage of indicia on the web, and a brake operated by the photo-electric cell to stop the travel of the web in positional relationship to the indicia thereon.
8. A web registering device comprising a 50 pair of web feed rolls intermittently operated once during each machine cycle with a surface speed slightly in excess of that required for normal web feeding operations, a web brake, a spring tending to set the

brake and stop the feeding of the web irrespective of the rotation of the feed rolls, an electromagnet, an armature controlled by the electromagnet and connected to the brake so as to overcome the spring and hold the brake 70 out of contact with the web while the electromagnet is activated, a photo-electric cell controlled by the passage of indicia on the web, an electric circuit connecting the cell and the electromagnet so that passage of an indicium 75 de-energizes the electromagnet and thus releases the armature and sets the brake, and a member having a lost motion connection with the armature and cam operated in timed relation with the feed rolls to replace the armature against the electromagnet.

In testimony whereof I have affixed my signature.
